REMOVAL OF VANADIUM AND/OR SODIUM FROM PETROLEUM BY HYDROGENATION IN THE PRESENCE OF BAUXITE

Frederick William Bertram Porter and John Welford Hyde, Sunbury-on-Thames, England, assignors to The British Petroleum Company Limited

No Drawing. Application December 28, 1951,
Serial No. 263,956

Claims priority, application Great Britain
January 15, 1951

5 Claims. (Cl. 196—35)

This invention relates to the removal of vanadium and/or sodium from petroleum and petroleum products.

In the specification of our co-pending British application No. 16540/49, we have described a process for the removal of vanadium from petroleum products wherein the petroleum product is subjected to treatment with hydrogen in the presence of a sulphur-resistant hydrogenation catalyst and under conditions of temperature and pressure such that the vanadium is deposited on or incorporated with the catalyst.

We have now discovered a process by means of which vanadium and/or sodium may be substantially or completely removed from petroleum or petroleum products. The process may be successfully applied to crude petroleum, uses a comparatively cheap catalyst, and may be operated with substantially complete removal of vanadium and sodium for operating periods of at least 600 hours.

According to invention, sodium is removed from petroleum or a petroleum product by contact with bauxite under conditions of temperature and pressure such that the sodium is deposited on or incorporated with the bauxite.

The degree of sodium removal is appreciable at a temperature of 650° F. and increases progressively with increase of temperature until it is virtually complete at 850° F. The preferred temperature is 780° F.

At 780° F. the degree of sodium removal is appreciable even at atmospheric pressure and increases with increase of pressure until an apparent maximum of approximately 85% is reached in the range 100–200 p. s. i. g.

If the feedstock contains vanadium in addition to sodium, it has been found that the degree of vanadium removal is small rising from nil at 650° F. to approximately 15% at 800° F. At 850° F. there is an increased removal of vanadium but increased decomposition of the feedstock results in short process period due to deposition of carbon. At a temperature of 780° F. the removal of vanadium increases with pressure from 10% at atmospheric pressure to an apparent maximum of 28% in the range 100–200 p. s. i. g.

It has been found that the degree of sodium removal may be maintained and the degree of vanadium removal considerably increased by contacting the feedstock with bauxite in the presence of hydrogen.

According to a further feature of the invention, therefore, both sodium and/or vanadium is/are removed from petroleum or a petroleum product by contact with bauxite in the presence of hydrogen under conditions of temperature and pressure such that the sodium and/or vanadium is/are deposited on or incorporated with the bauxite.

The sodium is in general removed far more readily than the vanadium so that it is the conditions for the removal of vanadium that are critical. Removal of vanadium is small below 700° F. but increases rapidly over the range 700–800° F. There is a consumption of hydrogen in the

2

process which increases rapidly at temperatures above 750° F. so that in practice it has been found advantageous to operate at a maximum temperature of 780° F.

The pressure is preferably maintained in the range 5 800–1000 lb./sq. in.

It has been found that about 70% of the vanadium in a Kuwait crude oil containing 22 p. p. m. of vanadium may be removed during a catalyst life of at least 650 hours with a hydrogen consumption of 65 C. F./B., under the 10 following conditions.

Space velocity	v./v./hr.	1.0
Temperature	°F.	780
Hydrogen recycle rate	C. F./B.	4000
Pressure	p. s. i. g.	1000

Under these conditions 90–95% of the sodium originally present in the crude oil is removed.

Little advantage is gained by increasing the recycle rate 20 above 6000 C. F./B. but when the recycle rate is reduced below 2000 C. F./B. the residual vanadium content increases considerably.

The process of the invention is particularly advantageous as applied to the treatment of crude petroleum. 25 The application of the so-called hydrofining process to crude petroleum has been described in the specification of co-pending British application No. 22050/50, corresponding to U. S. application No. 245,046 filed September 4, 1951, now abandoned, the use of cobalt molybdate type catalysts being preferred. The higher boiling fractions of crude petroleum often contain traces of vanadium and sodium and it has been shown that in the hydrofining of petroleum and petroleum residues substantial proportions of the vanadium and sodium are removed by and deposited on the cobalt molybdate catalyst, and that this deposition causes a steady decline in catalyst activity with hours on stream which is not wholly recovered on regeneration in the conventional manner. The treatment of the crude petroleum or residue in accordance with the present invention will therefore result in considerable improvement in the hydrofining process as applied to these materials. A two-stage process consisting of the treatment of a crude petroleum or residue in accordance with the present invention followed by the hydrofining of the treated crude petroleum or residue forms the subject of co-pending British application No. 6619/51.

Traces of vanadium and sodium also occur in petroleum feedstocks, such as wax distillates, which are subjected to cracking in the presence of a cracking catalyst, which may be a natural clay, such as montmorillonite, or a synthetic material, of which silica-alumina gel is typical, for the production of lower boiling products. In this case, the presence of the vanadium and sodium in the feedstock causes a slow decline in catalyst activity which is not recovered on regeneration and which eventually necessitates the replacement of the catalyst. The present invention therefore includes within its scope a process which comprises subjecting a catalytic cracking feedstock to treatment for the removal of vanadium and/or sodium as hereinbefore described, followed by catalytic cracking of the treated feedstock.

The invention will now be described with reference to the following examples.

Example 1

65 A petroleum residue representing 52% by volume on Iranian crude oil was passed over roasted Indian bauxite at a space velocity of 1.0 v./v./hr. and at temperatures of 650, 700, 750, 800 and 850° F. Each run was of 70 50 hours duration except the last one, at 850° F., which had to be terminated owing to excessive coke formation. The results are set out in Table I.

We claim:

1. A process for removing sodium and vanadium from a petroleum hydrocarbon selected from the group consisting of crude petroleum, petroleum residue, and wax distillate, which comprises contacting said hydrocarbon with a catalyst consisting essentially of bauxite and in the presence of hydrogen at a temperature within the range from about 700 to 800° F. and at a pressure within the range of about 800 to 1000 p. s. i. gauge, whereby the sodium and vanadium contained in the hydrocarbon are contained on the bauxite catalyst, and recovering a substantially sodium and vanadium-free hydrocarbon.

2. A process in accordance with claim 1 in which the hydrogen is passed in at a rate of about 2000 to 6000 C. F./B. and the space velocity of the hydrocarbon is 15 between 1 and 3 v./v./hr.

3. A process in accordance with claim 1 wherein the petroleum hydrocarbon is a petroleum residue.

4. A process in accordance with claim 1 wherein the petroleum hydrocarbon is crude petroleum.

5. A process in accordance with claim 1 wherein the petroleum hydrocarbon is a wax distillate.
